LOG LIFTING JACK

Elmer Schnadt, Sumner, Iowa

Application July 12, 1948, Serial No. 38,199

3 Claims. (Cl. 254—135)

1

The present invention relates to new and useful improvements in jacks and more particularly to a log lifting jack embodying means for engaging and raising one end of a log to hold the same in an elevated position above the ground while the log is being sawed to prevent the binding of a saw in the saw cut.

An important object of the invention is to provide a portable log lifting jack which may be easily and quickly moved into a desired position with respect to a log while sawing the same.

More specifically the invention embodies the provision of a pair of posts positioned at opposite sides of a log with a chain anchored at its ends to the respective posts to provide a saddle in which a log is seated and providing one of the posts with jacking means whereby the log may be raised into a desired elevated position.

A further object of the invention is to provide a device of this character of simple and practical construction, which is strong and durable, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view showing the log lifting jack in position for supporting a log thereon;

Figure 2 is a top plan view;

Figure 3 is a front elevational view of the stationary post of the jack device;

Figure 4 is a similar view of the vertically adjustable posts of the jack device;

Figure 5 is a transverse sectional view taken substantially on a line 5—5 of Figure 4, and;

Figure 6 is a transverse sectional view taken substantially on a line 6—6 of Figure 3.

Referring now to the drawings in detail wherein for the purpose of illustration I have disclosed a preferred embodiment of the invention the numeral 5 designates the stationary part of the jack device and the numeral 6 designates the vertically adjustable or lift part of the device, the parts 5 and 6 being portable for positioning at the opposite sides of a log 7.

The part 5 comprises a channel iron post 8 suitably secured on a base 9 for supporting the post in an upright position, the post 8 having a vertical slot 10 therein and to the outer sur-

2

face of the post is secured a plurality of bars 11 in a horizontal position and vertically spaced with respect to each other and placed cross-wise or in bridging relation with respect to slot 10.

5 The lift part 6 of the device comprises a base 12 to which a pair of vertical angle iron guides 13 are suitably secured in spaced parallel relation with respect to each other and between which a hydraulic or other suitable conventional type of 10 jack 14 is positioned for resting on the base 12. The jack 14 includes a jack post 15 operated in a reciprocating movement in the usual manner by the jack and to which is suitably secured a lift plate 26 positioned vertically at one side of the 15 post 15 and which may be composed of laminations 27 including a relatively narrow intermediate lamination 28 to form vertical grooves 29 at the side edges of the lift plate receiving the opposed edges of the guides 13 for sliding thereon.

20 The construction of the lift plate 26 also includes a bar 30 which projects outwardly from one surface of the lift plate and formed at its outer edge with inclined notches 31.

Inclined braces 32 extend from the base 12 to 25 the upper portion of the guides 13 to hold the same rigid.

A chain 33 forms a sling under the log 7 with one end of the chain inserted in the slot 10 of post 8, the chain being anchored in the slot by 30 one of the links 34 positioned cross-wise of the slot and supported on one of the cross bars 11.

The other end of the chain is attached to the lift plate 26 of the jack 14 by engaging a ring or the end link 35 of the chain in one of the notches 31 of the bar 30 carried by the lift plate.

The operation of the jack 14 in the usual manner by the handle 36 thereof will raise jack post 15 and lift plate 26 which slides in guides 13 40 to lift the adjacent end of the chain 33 and thus raise the log into a desired elevated position to support one end of the log while sawing the same.

In view of the foregoing description taken in conjunction with the accompanying drawings it 45 is believed that a clear understanding of the device will be quite apparent to those skilled in this art. A more detailed description is accordingly deemed unnecessary.

It is to be understood, however, that even 50 though there is herein shown and described a preferred embodiment of the invention, the same is susceptible to certain changes fully comprehended by the spirit of the invention as herein described and the scope of the appended claims.

Having described the invention, what is claimed as new is:

1. A log lifting apparatus comprising in combination, a sling for a log, an upstanding sling attaching member at each side of a log one of said attaching members including vertically spaced apart anchoring means for selective anchoring engagement of one end of the sling thereto, quick-releasable anchoring means carried by the other of said attaching members for the other end of the sling, and jacking means for said last-named anchoring member.

2. A log lifting apparatus comprising in combination, a portable post positioned at one side of a log and having a vertical slot therein, vertically spaced apart horizontal bars secured to the post across the slot, a chain extending under the log with one of its links anchored crosswise in the slot over one of said cross bars, a jack positioned at the opposite side of the log, and means carried by the jack for attaching the adjacent end of the chain thereto.

3. A log lifting apparatus comprising in combination, a portable post positioned at one side of a log and having a vertical slot therein, vertically spaced apart horizontal bars secured to the post across the slot, a chain extending under the log with one of its links anchored crosswise in the slot over one of said cross bars, a jack positioned at the opposite side of the log, and including an upstanding bar having inclined notches in one edge for selectively attaching the adjacent end of the chain thereto.
